I. K. WATTS

DIAPHRAGM SUPPORT

Filed July 11, 1924

Fig. 1.

UNITED STATES PATENT OFFICE.

IONE K. WATTS, OF NEW YORK, N. Y.

DIAPHRAGM SUPPORT.

Application filed July 11, 1924. Serial No. 725,450.

To all whom it may concern:

Be it known that I, IONE K. WATTS, a citizen of the United States, and a resident of the city of New York, borough of Manhattan, in the county and State of New York, have invented a new and Improved Diaphragm Support, of which the following is a full, clear, and exact description.

This invention relates to clothing and particularly to what may be termed a diaphragm support and has for an object to provide a simple construction which may be adjusted vertically on the body in different positions and maintained substantially in any adjusted position with comfort.

Another object of the invention is to provide a band in the nature of a diaphragm support or reducing band which co-acts with the corset in such a manner that the band is held against either downward or upward movement when once positioned.

In the accompanying drawing—

Figure 1 is a perspective view of a corset with a support embodying the invention shown in connection therewith.

Figure 2 is an enlarged perspective view of the diaphragm support shown in Figure 1.

Referring to the accompanying drawing by numerals, 1 indicates a corset of the usual well known variety now on the market provided with a front opening 2 having the usual clasps or fastening members and a rear opening 3 having the usual lacing 4. Arranged interiorly of the corset 1 is a supporting band 5 which is adapted to act as a supporting member for supporting the diaphragm and associated parts of the body and as means for holding the front stay of the corset in its normal position and against protruding, and also under some circumstances as a reducing band when properly located. This band is shown more in detail in Figure 2 and is provided with flexible members 6 and 7 formed of a good grade of cloth provided with suitable eyelets 8 and 9 at the back for receiving the lacing 10 whereby the band may be adjusted different sizes to secure the proper fit or tension. At the front, the sections or flexible members 6 and 7 are connected with the plate 11 by having the ends extending through the

slots 12 and 13 and then stitched in position by suitable lines of stitching 14 and 15. By reason of the slots 12 and 13, there is presented a central bar 16 on which encircling members 17, 18 and 19 are slidably mounted. Each of these encircling members is provided with an apertured upstanding member 20 carrying a fastening link 21 which is preferably provided with a bowed out section 22 normally fitting the aperture 23 of the member 20. The various fastening links 21 are preferably made of resilient metal whereby they may pull longitudinally and then turn to the dotted position shown in Figure 2 whereby they may be readily inserted between the abutting sections of the corset 1 at the front. After this has been done, the links 21 are turned to their correct position as shown in Figures 1 and 2.

It will be noted that the various links 21 and the projecting members 20 are arranged either above or below certain of the fastening means 24 of the corset 1 whereby the plate 20 and also the support 5 cannot work their way up or down when the device is in use. When the support is arranged substantially as shown in Figure 1, it acts to confine the body adjacent the diaphragm and acts as a support in a certain sense for the diaphragm and the upper part of the body. If desired, the support could be moved much higher and caused to act merely as a confining or reducing belt rather than as a support. The plate 11, links 21 and associated parts, function in the usual manner for maintaining the support in the desired adjusted position. Three links with their members 20 are shown in Figures 1 and 2 but it is evident that a larger or even less number could be used without departing from the spirit of the invention. The invention has been shown on a rear lace corset for the purpose of illustration but it will be evident that the device could be used equally well on a front lace corset or similar garment.

What I claim is:

1. A diaphragm support, comprising a belt structure including lacing for adjusting the size, a plate connected with said belt structure, said plate having a plurality of movable upstanding members adapted to extend between the front edges of the corset.

when the device is in use, and a retaining link connected with each of said upstanding members.

2. The combination with a corset open at the front and provided with clasps, of a supporting belt arranged interiorly of the corset, said belt being provided at one point with lacing, a plate connected with said belt opposite the front opening of the corset, a plurality of sliding members mounted on said plate and projecting through said front opening, and swinging links mounted on each of said projections acting as retaining members in connection with the clasp of the corset whereby the belt cannot move upwardly or downwardly independently of the corset.

3. In a diaphragm support, a plate provided with a pair of slots extending from near one end to near the other end, a plurality of sliding encircling members positioned on the bar formed between said slots, each of said encircling members being provided with an apertured upstanding member, and a link extending through each of said apertures, each of said links having a pressed out central portion whereby the links will normally remain projected substantially an equal distance on each side of the respective projections.

4. A diaphragm support, comprising a belt, a plate connected with said belt, a plurality of upstanding members slidably

mounted on the plate so as to be moved longitudinally thereof or in a direction transversely of the belt, and means connected with each of the sliding members acting as retaining buttons.

5. The combination with a corset laced at the back and connected together at the front by fastening members, of a belt formed in two sections, lacing for lacing said sections together at one point, said lacing being positioned adjacent the lacing of the corset, a plate connected to the opposite ends of each of said sections, said plate being positioned in back of the front opening of the corset, and a plurality of sliding members carried by said plate, said sliding members acting as buttons with part thereof projecting to the outer surface of the corset through the front opening and overlapping the corset whereby independent up and down movement of the belt is prevented.

6. The combination with a corset open at the front and provided with a front stay, of a belt adapted to be positioned interiorly of the corset, means connected with the belt projecting through the front opening of the corset, and means acting as buttons connected to said projecting means adapted to overlap part of the front corset and said stay for holding said stay in its normal position and against protruding.

IONE K. WATTS.
